UNITED STATES PATENT OFFICE.

FERDINAND BLAUSS, OF NEW YORK, N. Y.

DESIGN FOR A KITE.

SPECIFICATION forming part of Design No. 24,989, dated December 17, 1895.

Application filed October 8, 1895. Serial No. 565,079. Term of patent 3½ years.

To all whom it may concern:

Be it known that I, FERDINAND BLAUSS, a citizen of the United States, and a resident of New York, in the county of New York and 5 State of New York, have invented and produced a new and original Design for Kites, of which the following is a specification, reference being had to the accompanying drawings, forming part thereof, in which—

Figure 1 is a front view of the kite formed according to my improved design; and Fig. 2, a back view thereof, these two views being deemed necessary to fully illustrate my design.

The back of my new and original design for kites is, as shown in Fig. 2, substantially the same as with kites of the ordinary design, being composed of the usual frame comprising the transverse rod A and the diagonal 20 rods B and C, which cross the transverse rod A, as shown, and the body D of the kite being composed of the usual material and bounded by the bottom line E, the side lines F and G, the inwardly and upwardly inclined lines H and K, and the top line L.

The side portions F and G are but slightly inclined from the cross-rod A to the bottom or lower ends of the diagonal rods B and C, and the lines H and K are inclined inwardly 30 and upwardly from said cross-rod A to the top transverse rod L.

The leading feature of my new and original design for kites consists in the configuration of the front of the body portion thereof, as 35 shown in Fig. 1, said front being provided centrally with a vertical line M, which ex-

tends from the bottom to a level with the top of the side lines F and G and the transverse line m, which extends from the top of the vertical line M to the top of the side line F 40 and the outwardly and upwardly inclined line m', which extends from the top of the central vertical line M outwardly and upwardly to the top of the line K, by means of which the front of the kite is made to represent a house, 45 one side, one end, and one side of the top or roof of which are shown, another characteristic feature being the representation of doors N at the lower corners of the end of the house, the windows n above said doors, and 50 the window n' above the windows n, and also the representation of a door O at the bottom left-hand corner of the side of the house, a window P adjacent thereto, and the windows R above the door O and the window P, that 55 portion of the roof above the side E being also provided with windows S at the lower side thereof and a chimney T at one side of the roof and above the windows S.

I claim and desire to secure by Letters 60 Patent—

The design for kites herein shown and described.

In testimony that I claim the foregoing as my invention I have signed my name, in presence of the subscribing witnesses, this 7th day of October, 1895.

FERDINAND BLAUSS.
